UNITED STATES PATENT OFFICE.

FRANK E. WELLMAN, OF KANSAS CITY, KANSAS, ASSIGNOR TO KANSAS CITY GASOLINE COMPANY, OF KANSAS CITY, KANSAS, A CORPORATION OF KANSAS.

APPARATUS FOR HEATING OILS.

Application filed June 3, 1922. Serial No. 565,633.

My invention relates to cracking processes and stills for transforming heavy hydrocarbons having a high boiling point into other hydrocarbons having a lower boiling point.

- 5 It has for its object the improvement of such processes and stills in the following particulars: to produce a greater heating surface relatively to the content of the still, and to prevent foaming with such an arrangement; to
- 10 provide for the use with a pipe still of the system of heating disclosed in my prior co-pending applications, Serial No. 523,062, filed December 17, 1921, Patent No. 1,576,563 and Serial No. 532,873, filed January 15, 1922, patent No. 1,581,896; to provide for a circular arrangement of vertical still pipes, in order to gain the full advantages of the aforesaid system of heating; to provide for equalizing levels and for uniformly
- 20 feeding a circular series of still pipes; to provide for control of the air supply for such a pipe still, and in connection therewith to provide suitable means for supporting a rotating heating means.
- 25 Further objects and advantages of my invention will sufficiently appear from the detail description hereinafter.

I attain my objects by forming a circular series of still pipes, which may be in one, two, or more rings as desired. These may be individual tubes connected through headers or tanks at the top and bottom, or they may be connected alternately at top and bottom so as to form a series coil. Within the ring of pipes is built a liner of refractory material, such as fire brick, and outside the ring of pipes is a larger wall or enclosure of similar material. These are connected at the top so that the still pipes hang down in an annular chamber between the liner and the outer wall. The walls of this chamber are closer together at the top than at the bottom, the outer wall being in the form of the frustum of an upright cone, while the inner wall or liner is in the form of the frustum of an inverted cone. Expansion tanks are provided at the upper ends of the coils, and connected thereto by radial pipes. A central equalizing and feed tank is supported above the still and has radial connections to all the still pipes, and to the expansion tanks as well. Heating is effected by means of the rotating burner described in my prior applications above referred to, and a hermetic seal is provided for air entering the furnace,

whereby it is directed properly to the burner but prevented from entering the still space, in which it would mingle with and dilute the products of combustion, thereby lowering the temperature.

My invention is illustrated in the accompanying drawings, in which:

Fig. 1 is a vertical section on the line 1—1 of Fig. 2;

Fig. 2 is a plan view;

Fig. 3 is a transverse section on the line 3—3 of Fig. 1; and

Fig. 4 is a detail sectional view on an enlarged scale of the burner, its supporting shelf and associated parts.

Fig. 5 and 6 show modifications of the burner arrangements.

Referring to the drawings, 1 designates a series of vertical still pipes, which may be for example 7 inches in diameter and approximately 40 feet in length. These are arranged in a circle, being supported preferably at their upper ends. 3 is an inner wall or liner of refractory material, in the form of a frustum of an inverted cone. 4 is the outer furnace wall of the same material in the form of the frustum of an upright cone. It is to be observed that in cross section at any point these inner and outer walls are circular as shown in Fig. 3.

At their lower ends, the still pipes 1 are all secured to a ring manifold 5, from which draw-off pipes 6 are led out through the furnace walls 4. At their upper ends the still pipes are closed by flanged and bolted cap plates 7, or other suitable means, these being removable for cleaning purposes, but in practice I may use a header or manifold for all these pipes similar to the lower ring 5 in Figs. 1 and 3, and in such case, one or both of the manifolds at top and bottom may be made large enough to permit the entrance of workmen for cleaning out the pipes.

Inasmuch as the still pipes have very considerable content by reason of their length, but a very small surface for the yielding up of vapor, it is necessary to provide means for preventing foaming, which I do in the form of tanks 8—8^a—8^b—8^c, shown in Figs.

1 and 2. These tanks are connected to the still pipes by radial tubes 9—10, the former lying below the normal liquid level and the latter lying above it. In addition to these connections, the tanks, 8, 8^a, etc., are connected by pipes 11 containing expansion

joints 12 with the central equalizing and feeding tank 13. Below the liquid level this tank is connected to all of the still pipes by radial tubes 14. A gauge glass or other 5 convenient form of indicator 15 is provided to show the liquid level in the tank 13.

The usual vapor line and make-up or feed 10 pipe connections are shown at 16 and 17, connected to the tank 13, from which the feed of fresh material is equalized to all 15 of the still pipes and the liquid level maintained the same throughout the system.

The fuel feed and burner mechanism is 15 marked 18, 19, 20, 21 and 22. The pipe 20 lengths 18, 19 and 21 are double, that is to say an oil pipe is secured concentrically within the steam pipe, so that at the burner 22 oil and steam are both supplied as determined by suitable valves connected to 25 the supply pipe 18. Centralized with respect to the still is a swivel joint 23, the outer section of which is connected to the pipe 19 and is rotated by means of a worm 24 driven by shaft 25 carrying a sprocket 25 wheel, 26. The pipe section 21 drops through an annular slot in the guard plate 20, closing the annular opening 20^a in the top of the furnace. The lower end of the pipe 21 (see Fig. 4), passes through an 30 opening in the rotating shelf 27 where a bend is produced to form a trailing burner arm, 28 (see Figs. 3 and 4), which carries a burner composed of a pair of feeder arms 33 and 35, one carrying oil and the other 35 steam, and a burner head 34. The arms 33 and 35 are connected to the inner and the outer pipes, respectively, of the concentric pair 18—19—21.

The burner arm 28 lies beneath the shelf 40 27, its end passing up through an opening therein and carrying a T-fitting 32 to which the arms 33 and 35 are secured. The shelf 27 is annular, pierced with air openings 27^a, adjacent the burner, and has depending annular flanges 29 each dipping into liquid 45 31 in an annular trough 30, constituting the top member of an hermetically sealed enclosure 39, which communicates with the outer air through pipe 40, (see Figs. 1 and 50 3), the volume of air supply being regulated by means such as the damper 41, controlled as by an operating rod 42 from the outside. The chamber 39 is of such size and shape that workmen may enter it through 55 a suitable manhole for adjustment of the burners. When the still is in operation the air chamber and surrounding parts are cool, even the brick work in walls 3 and 4 remaining dark and at a low temperature compared 60 with that of cracking stills as ordinarily fired.

The burner system, including the shelf 27, is rotated at a regular rate of speed by top and bottom gears. At the top, worm 24 is 65 carried on shaft 25, fitted with sprocket 26.

At the bottom the gear 36 meshes with crown teeth around the outer edge of shelf 27, and is driven through the shaft 37 by motor 50, which also drives the upper shaft 25 through sprocket chain 38 or equivalent means. By suitably relating the worm sprockets, gears and motor, the entire system is rotated at a uniform speed and without racking or strain. The shelf 27 may of course be given additional bearing support 70 in or out of the troughs 30, and the down pipe 21 may be duplicated at 180° around the shelf to give a hanging frame, if desired. The specific arrangement of the burner system is immaterial so long as it performs the 80 functions described. The burner throws its flame across the inner sides of the still pipes 1, around which it is rotated at such a rate of speed that any given spot in any still pipe is within the directly heated area during 85 each cycle of rotation, for a period less than that in which destructive heating would occur. Since the air supply to the annular combustion space is only by way of openings 27^a, there is no admixture of atmospheric air with the products of combustion, and the furnace temperature and operating 90 conditions therein, are therefore both uniform and efficient. This effects a substantial saving in fuel, and also produces a more 95 uniform output.

The operation of this system is continuous, fresh oil being added through pipe 17, to make up for withdrawals through vapor line 16, or draw-off pipes 6.

In Figure 5 I show a modified arrangement of the burner with respect to the still pipes, whereby the flame may be applied to the lower ends of the pipes or to the header 5 connecting them. It is to be understood that the header may be omitted and the flame may be trailed over the bottoms of the pipes themselves if desired, and for cracking some material this would have advantages. In the claims I shall specify that the flame is applied at the bottom of the still, but this is to include both the arrangements shown in Figures 1 and 5.

In Figure 6 I have shown in diagram a modified arrangement of the heating system in which a plurality of burners are separately fed and separately controlled, and for simplicity in the drawing I have shown these fed and driven from the bottom instead of the top of the still, also, as in Figure 5, the flame plays around the lower ends of the still pipes 1. In this figure, the burners are duplicated; being fed through concentric oil and steam pipes separately controlled by separate valves, so that either one or both may be used as desired. This multiplication of burners renders possible a corresponding multiplication of heating periods and it is to be understood that there may be any desired number of burners, fed in 115 120 125 130

any suitable or well understood manner, movable together as shown herein, or separately as required by special conditions. The mechanical detail of such arrangements 5 will be obvious to those skilled in the art after reading this description.

I claim:

1. A still for the treatment of hydrocarbon oils comprising a plurality of vertical 10 pipes arranged in a circle, concentric annular walls within and without said circle, and means for applying heat intermittently and individually to the still pipes and their contents around the circle in periodic rotation.
2. A still for the treatment of hydrocarbon oils comprising a plurality of vertical 15 pipes arranged in a circle, concentric annular furnace walls within and without said circle, and a source of heat arranged to be continuously moved in relation to the assemblage of said pipes and furnace walls to apply heat intermittently and individually to each of said pipes in periodic rotation at points above the lower ends thereof.
3. A still for the treatment of hydrocarbon 20 oils comprising a plurality of vertical pipes arranged in a circle, concentric annular furnace walls within and without said circle, a source of heat arranged to be moved around between the pipes and the inner still wall and consisting of a fuel feed pipe at the top of the furnace, a drop member connected therewith and passing down between the pipes and the inner wall, a traveling 25 burner arm near the lower ends of the pipes connected with the drop member to receive fuel supply therefrom, an annular hermetically sealed air chamber near the bottom of the furnace extending around between the pipes and the inner wall and having a movable part arranged to move with the burner with air ducts adjacent to the burner for supplying air thereto from said air chamber.
4. The still as claimed in claim 3 with means for regulating the supply of air to said air chamber.
5. A still for the treatment of hydrocarbon 50 oils comprising a plurality of vertical pipes arranged in a circle, concentric annular furnace walls within and without said circle inclined toward the upper ends of the pipes to form an upwardly tapered annular chamber, and a heating burner near the bottom of the chamber.
6. A still for the treatment of hydrocarbon oils comprising a plurality of vertical 55 pipes, concentric annular furnace walls within and without said circle, and a source of heat arranged to be moved around between the pipes and the inner still wall, said source of heat consisting of a fuel feed pipe at the top of the furnace, a drop member connected therewith and passing down be-

tween the pipes and the inner wall, a traveling burner arm near the lower ends of the pipes connected with the drop member to receive fuel supply therefrom and an annular hermetically sealed air chamber below the burner arm extending around between the pipes and the inner wall and having a movable part arranged to move with the burner with air ducts adjacent the burner for supplying air thereto from the air chamber, and means for uniformly rotating said drop member and said movable air chamber part.

7. A still for the treatment of hydrocarbon oils comprising a plurality of vertical 75 pipes arranged in a circle, concentric annular furnace walls within and without said circle, combustion means for heating said pipes near the lower ends thereof, means for taking off the products of combustion near the upper ends thereof, and a plurality of separate expansion tanks each connected to the upper ends of a separate group of the still pipes and situated at such points as to carry the same liquid level with greater surface thereof than is possible in the 80 pipes and thereby prevent foaming.

8. The still claimed in claim 7 with the addition of a central equalizing and feed tank connected to each of the still pipes through a separate connection in the lower 85 part thereof, and to each of the expansion tanks by separate connections in the upper part thereof.

9. The still claimed in claim 7 with the addition of a central equalizing and feed 90 tank connected in the lower part thereof to each of the still pipes and by separate connections in the upper part of same to each of the expansion tanks, connections between the still pipes and the expansion tanks in the lower part thereof and other separate connections therebetween in the upper part of the same, whereby the entire system is equalized for both liquid and vapors.

10. A still having subdivided oil containing means arranged to present an annular heating area having vertical walls, and a combustion heater adapted to pass over the said area and trail its flame in substantially a horizontal plane against the vertical walls 115 of the heating area.

11. The still claimed in claim 10, in which the containing means is composed of a plurality of pipes arranged in a circle.

12. A heating system for pipe stills, having stationary liquid containing pipes and a burner adapted to pass a flame intermittently and individually over the heating surfaces of the pipes in periodic rotation.

In testimony whereof I hereunto affix my 125 signature.

FRANK E. WELLMAN.
